CLAIM

The ornamental design for a logo for jewelry, clothing, leather goods, and personal accessories, as shown and described.

DESCRIPTION

FIG. 1 is a top, front perspective view of a first embodiment of the new design for a logo for jewelry, clothing, leather goods, and personal accessories;

FIG. 2 is a top, back perspective view;

FIG. 3 is a front view of FIG. 1;

FIG. 4 is a back view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a top, front perspective view of a second embodiment of the new design for a logo for jewelry, clothing, leather goods, and personal accessories;

FIG. 10 is a top, back perspective view;

FIG. 11 is a front view of FIG. 9;

FIG. 12 is a back view of FIG. 9;

FIG. 13 is a left side view of FIG. 9;

FIG. 14 is a right side view of FIG. 9;

FIG. 15 is a top view of FIG. 9;

FIG. 16 is a bottom view of FIG. 9; and,

FIG. 17 is a top, front perspective view of a third embodiment of the new design for a logo for jewelry, clothing, leather goods, and personal accessories.

The broken lines in the figures form no part of the claimed design.
